KEYLESS IGNITION SWITCH

Ewart Ellis Saucier, El Paso, Tex.

Application July 17, 1939, Serial No. 285,011

2 Claims. (Cl. 200—45)

This invention relates to a keyless ignition switch, the general object of the invention being to provide rotary means for adjusting parts to a certain position which is indicated by combination indicia forming part of the switch after which the parts can be adjusted to close the switch so that one must know the combination before he can close the ignition switch.

Another object of the invention is to provide means whereby the parts can be reset so as to operate them with a new combination.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings where-in like characters denote like or corresponding parts throughout the several views, and in which:

Figure 1 is a fragmentary view of an instrument board showing the invention applied thereto.

Figure 2 is a view looking toward the rear part of the switch with the casing removed.

Figure 3 is a section on the line 3—3 of Figure 1.

Figure 4 is an edge view with parts in section.

Figure 5 is a view of the rotary cap-like member.

Figure 6 is a view of the ring-shaped member in which the cap-shaped member rotates.

In these drawings the letter A indicates a part of the instrument board of an automobile or other supporting member and the numeral 1 indicates a substantially conical shaped member attached to the member A by a bolt 2 passing through a tongue 3 which extends from an edge portion of the member 1. A ring-shaped member 4 provided with a bayonet slot 5 has the oppositely extending arms 6 thereon, said arm and an edge portion of the member 4 contacting the underside of the member A and the bolt 2 passes

through one of the arms 6 and a second bolt 7 passes through the supporting member A and the other arm 6. This member 4 forms a circular space on the underside of the supporting member and in rear of the member 1 and a cup-shaped member 8 fits in this space and has a centrally arranged hole 9 therein through which passes an enlarged part of a bushing 10, a threaded part of which passes through a hole in the supporting member A and in the central part

of the member 1, this member 1 being provided with an enlarged centrally arranged recess 11 into which the small end of the bushing projects. A nut 12 is threaded on said small end of the bushing to hold it in place and said bushing rotatably holds the cup-shaped member 8 in place as shown in Figure 3. This member 8 is formed with a notch 13 which in one position of the member 8 will register with the inlet portion of the bayonet slot and said member 8 is also provided with an ear 14 which extends from an edge of the flange of the cup-shaped member. The member 1 forms a dial which is provided with radiating lines 15 which radiate from the opening 11 and adjacent the large end of the member 1 combination characters such as the letters 16 are placed opposite the lines 15. A circular member 17 is movably arranged in the recess 11 and has a knob 18 at its outer end. A shank 19 passes through the bushing 10 and has a threaded part passing through the member 17 and its knob 18, this shank being connected with the member 17 by a socketed screw 20 threaded on that part of the shank which passes through the knob and engaging the knob so that when the screw is threaded home the shank is caused to turn with the knob and the member 17. A washer 21 is threaded on the shank and when the screw 20 is tightened the member 17 with its knob 18 are held firmly to the shank so that the shank 20 will turn when the member 17 is turned. The shank is provided with a right angular part 19'. The switch is shown at 8 and includes the contact strip 22 and the contact strip 23 insulated from each other as shown with the strip 23 having the angle extension 24 having the block 25 of non-conductive material located adjacent the bayonet slot 5 of the member 4. A marker or arrow 26 is placed on the member 17, as shown in Figure 1 to cooperate with the dial.

When it is desired to close the ignition switch the knob 18 is pushed into the recess 11 and is then turned to the right to cause the part 19' of the shank 19 to strike the ear 14 of the cup-shaped member 8 and then continued turning of the knob will cause the part 19' to turn the member 8 in the member 4. This turning movement is continued until the arrow 26 comes even with the letter or character 16 which the operator knows is the correct stopping point of the turning movement. This will place the notch 13 in register with the outer part of the slot 5. Then the knob is turned to the left to a point where the arrow 26 will come opposite a character 16 which the operator knows is the second stopping

point. This will put the part 19' directly opposite the notch 13 and the outer part of the slot 5. Then the operator pulls the knob outwardly which causes the part 19' of the shank to enter 5 the notch and the bayonet slot and then the knob is given a slight turning movement to cause the part 19' to enter the inner portion of the bayonet slot and this causes the part 19' to strike the block 25 and force the contact points of the members 10 22 and 23 together to close the ignition circuit. This slight additional turning movement to cause the part 19' to enter the inner portion of the bayonet slot will act to cause the notch 13 to move out of register with the outer portion of 15 the bayonet slot and thus the part 19' is latched in the inner portion of the slot to positively hold the switch in closed position and prevent vibration of the automobile or other jars from causing the parts to move out of switch closing position. 20

When the switch is to be closed the knob is turned slightly to cause the part 19' to move out of the inner portion of the bayonet slot and then the knob is pushed inwardly and turned to place 25 the notch out of register with the slot 5.

Thus it will be seen that one must know the combination before he can correctly adjust the parts to close the switch and the combination can be changed whenever it is thought that unauthorized persons know the old combination. 30 The combination is changed in the following manner. The knob is turned as before described to place the part 19' of the shank in the inner portion of the bayonet slot. Then the screw 20 is loosened with a screwdriver or other tool to a sufficient amount to permit the knob and member 35 17 to turn relative to the shank. Then the knob is turned to the right which causes the part 19' of the shank to move back into the outer or 40 perpendicular part of the slot and into the notch 13. This prevents further movement of the shank but the knob is turned further to the right until the arrow stops at some new character. This new character or letter will match up the 45 slot and notch 13 for a new combination. Then the screw 20 is tightened to connect the shank with the knob and then the number of letters between the former right and left turn characters or letters are counted. Then count as 50 many letters to left from the new right turn letter and it will give the new left turn letter or character.

A casing 30 covers the parts on the rear of the supporting member and is held in place by the 55 bolts 2 and 7 and the casing may be provided with a hinge 31.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. In a device of the class described, a supporting member, a dial member on one face of the supporting member having a centrally arranged recess therein, a knob equipped rotary member in the recess, a shank connected with the rotary member and slidably and rotatably supported in the supporting member, a ring-shaped member on the other face of the supporting member 15 and having a bayonet slot therein, a cup-shaped member fitting in the ring-shaped member and rotatably mounted on the supporting member and having a notch therein, and a projection thereon, said shank having a bent part for engaging the projection when the rotary member is moved outwardly and rotated, rotary movement of the shank to a certain position placing the notch in the cup-shaped member opposite the bayonet slot after which the rotary member 25 is manipulated to place the bent part of the shank in the notch and bayonet slot and switch means closed by the placing of the bent part in the bayonet slot, said rotary member having a marker thereon for cooperating with parts on 30 the dial for indicating when the parts are adjusted to the proper position.

2. In a device of the character described, a supporting member, a substantially conical-shaped dial member fastened to one face of the 35 supporting member, said dial member having a centrally arranged recess therein, a knob equipped rotary member rotatably and slidably arranged in the recess and having a marker thereon for cooperating with the dial part for forming a combination assembly, a ring-shaped member attached to the opposite side of the supporting member and having a bayonet slot therein, a cup-shaped member rotatably arranged in the ring-shaped member and rotatably supported 40 from the supporting member and having a notch therein and a projection on its edge part, a shank adjustably connected with the knob equipped member and slidably and rotatably supported in the supporting member and having a 45 bent end for engaging the projection and also for entering the notch and the bayonet slot when the same are brought together by rotary movement of the cup-shaped member by the bent part of the shank, a switch closed by the entrance 50 of the bent part of the shank into the bayonet slot. 55

EWART ELLIS SAUCIER.
